PROCESS FOR REFINING VEGETABLE AND ANIMAL OILS AND FATS

Wilhelm Gensecke, Gonzenheim, near Frankfort-on-the-Main, Germany, assignor to American Lurgi Corporation, New York, N. Y., a corporation of New York

No Drawing. Application January 9, 1933, Serial No. 650,946. In Germany November 25, 1932

1 Claim. (Cl. 87—12)

This invention relates to a process for refining vegetable and animal oils and fats, and more particularly to that stage in the refining of the said oils or fats which is concerned with the separation of the impurities—hereinafter termed mucines or phosphatides—in colloidal solution in the crude oil, and of the fatty acids.

These mucines, phosphatides or the like, colloidally dissolved in the crude oil are separated out during the separation of the free fatty acids by saponification with alkali or other neutralizing agents. In that operation the mucines become enveloped in the flakes of the fatty-acid soap and greatly increase the bulk of the latter. These voluminous soap flakes only bed together loosely, on deposition, and therefore occlude a good deal of neutral oil.

In order to lessen this loss of neutral oil during the refining process, certain so-called pre-refining processes have been devised with the object of depositing and removing the colloidally dissolved mucines before proceeding to saponify the fatty acids. The known methods of such pre-refining consist in treating the oils or fats with aqueous solutions, for example of organic and inorganic acids, saline electrolytes, tanning agents and the like. The pre-refining by these known methods was performed in special apparatus, adapted, both in respect of material and shape, to the purpose in view. In the first place, the oil or fat to be treated was energetically stirred, in a vessel, with the medium (reagent) intended to precipitate the mucines, mechanical stirrers being usually employed, though air was also occasionally introduced. After the precipitant had operated for a sufficient time, the stirrers were put out of action, and the contents of the vessel left to rest. During this stage the separated impurities gradually settled down to the bottom of the vessel, in the form of a separate layer of turbid material which, when an acid had been employed as precipitant, also contained such acid. A source of difficulty in this treatment was caused by the circumstance that, on the one hand, a considerable time is advantageous for obtaining a satisfactory deposition of the impurities from the oil, whereas, on the other hand, the protracted contact with the precipitant—such as acid or dissolved saline electrolyte—impairs the quality of the oil. If the temperature be raised, in order to accelerate the deposition of the impurities, this measure also has an injurious effect on the quality of the oil. The restriction of this pre-refining to isolated instances in practice is explained by the aforesaid difficulty.

The turbid layer containing the mucines and other precipitated impurities was separated from the oil by drawing off said layer from the vessel by means of an outlet device provided at the lowest point of the vessel. In order to eliminate the final traces of precipitant (e. g. acid) from the oil, the latter had then to be repeatedly washed with hot water.

For the purpose of neutralization, the oil, freed from the mucines and the like, was next pumped into the actual refining apparatus, where the fatty acid was separated from the oil by saponification with alkali. Although the resulting oils were neutral and entirely free from mucines and like impurities, and a better yield of oil was obtained than by merely refining with alkali, without any special pre-refining, the quality of the oils was mostly inferior to those treated solely with alkali, that is to say, without pre-refining with acid or saline electrolytes.

According to the process of the present invention, the refining of vegetable or animal oils or fats is effected by means of the pre-refining process known per se with saline electrolyte solutions, and by neutralizing the fatty acids with alkali. In contrast, however, to the usual method of procedure, the pre-refining and neutralization are effected in a single working operation, inasmuch as the alkali required for neutralizing first the fatty acids and secondly those acids still present on account of the pre-treatment with acid-saline electrolytes, is added to the oil immediately after the action of the saline electrolyte solution or of the aqueous solution of saline electrolytes and acids, whereby the various mucines are precipitated. Consequently the precipitated mucines and the like together with the unconsumed portion of the saline electrolyte solution and the saline solution derived from the neutralization of the excess of acid—in cases where an excess of precipitant was used—remain in the oil and the impurities, the excess of precipitating agent and the soap stock formed by the neutralization of the fatty acid are precipitated together from the oil.

The present invention offers the following advantages in contradistinction with the known methods of working.

The mucines colloidally dissolved in the crude oil and other impurities are precipitated in flocculent form by the precipitating agent, namely a saline electrolyte solution or mixtures of various saline electrolyte solutions or acid saline electrolyte solutions. The flakes thus produced float in the oil which is free from mucine. In this con-

nection the acid saline electrolyte solution may either be added as such to the oil or fat to be treated, or the constituents of the electrolyte mixture can be added to the oil in succession, that is to say the acid is first added and then the saline electrolyte solution or vice versa. Immediately on precipitation of the colloidally dissolved mucine, alkali solution or any other suitable neutralizing agent is added to the oil. When employing an acid saline electrolyte solution as the precipitating agent any excess of acid that may be present is neutralized with the formation of the corresponding salt as is also the free fatty acid present. Flakes of soap are formed which include a small quantity only of neutral oil. The bodies precipitated out by the saline electrolyte solution or acid saline electrolyte solution, that is to say heavy flakes of mucine and any excess of saline electrolyte solution employed effect a rapid and efficient separation of the soap flakes from the oil and when the stirrer is stopped a thick layer of soap and mucine flakes is quickly formed, which includes considerably less neutral oil than the soap stock which is obtained by known methods of neutralization from crude oil. The soap stock settles down rapidly and an excellent yield of neutral oil free from mucine is obtained having a satisfactory consistency.

The soap stock consisting of soap flakes, entrained neutral oil, saline electrolyte solution and coagulated mucines and the like, can readily be separated into high grade neutral oil and high grade fatty acids by extraction with a solvent with subsequent treatment with acids. By extracting the soap stock with benzene or like oil solvents a solution of neutral oil and a mixture of soap and solvent is obtained. The oil solvent is distilled off from the neutral oil solution leaving the neutral oil. The extracted mixture of soap and oil solvent is decomposed by inorganic or organic acids into a mixture of fatty acids, solvent and saline solutions, whereupon the solvent is separated from the fatty acid and the saline solutions by distillation.

Almost all neutral oil included in the soap stock can be recovered in this manner. The high grade fatty acids produced in this method of working are particularly adapted for distillation. Decomposing the saponaceous oil, that is to say soap stock decomposed with acid, by means of the Twitchell reagent and by treatment in an autoclave, as is universally employed at present and in which the valuable neutral oil is destroyed, is avoided. The soap stock obtained in the neutralization processes in general employment at the present day contains the mucines and the like precipitated from the oil in quite a different form from that in which these substances are precipitated according to the process of the present invention. The mucines and the like were the cause of the difficulties which were encountered during the extraction of oil from soap stock recovered by the known processes.

A single apparatus only is required for the process of the present invention, so that the prime and running costs are considerably reduced. In the removal of mucine and neutraliza-

tion, hitherto usually carried out separately, there occurs during the separation of the refined oil and soap stock, approximately twice the loss of oil as in the case of the process of the present invention, in which only one separation is necessary of neutral oil and the deposited layer of mucine and soap. The separation of mucine may also be effected at a moderate temperature.

Example 1

1000 Kg. of soya bean oil containing 0.5% of free fatty acids are heated to 30° C. in an apparatus provided with stirrers. 7 litres of saturated magnesium sulphate solution are then added, whilst vigorous stirring is continued. The mixture is well agitated for 15 minutes, whereupon on the phosphatides colloidally dissolved in the crude oil separate out in the form of flakes. 5.5 Kg. of caustic soda lye of 20° Bé. are thereupon added and the whole is stirred at a temperature of 30° C. for 15 minutes. Fine grained soap flakes are formed which unite with the flakes of phosphatide. The oil is warmed to a temperature of 60° C. and simultaneously stirred. On stopping the stirrer the flakes of soap and phosphatide deposit in the form of a thick layer at the bottom of the vessel which contains a small quantity only of oil. The supernatant oil is then decanted off.

Example 2

1000 Kg. of earth nut oil are warmed to a temperature of 28° C. in a vessel provided with stirrers. 8 litres of an acid saline electrolyte solution consisting of 3 volumes of 30% sulphuric acid and five volumes of saturated sodium sulphate solution are then added with further vigorous stirring. The mucines colloidally dissolved in the crude oil are precipitated in a short time in the form of granular flakes which float in the pure oil. A quantity of caustic soda lye of 18° Bé. is thereupon added with continued stirring sufficient to neutralize both the excess mineral acid present in the oil and the free fatty acid also present. Fine grained soap flakes are formed including a small quantity of neutral oil. The oil is then warmed to a temperature of 55° C. with further stirring and is thereupon left to stand. The soap flakes separate out together with the flakes of mucine at the bottom of the refining apparatus in the form of a thick layer containing a small quantity only of oil. The oil is then decanted.

I claim:—

A process for removing mucines, phosphatides and the like and fatty acids from vegetable and animal oils and fats which comprises precipitating the mucines, phosphatides and the like with saline electrolyte solutions also containing an acid, and neutralizing the fatty acids and any acid derived from the previous treatment with alkali before separating off the precipitated impurities, the substances deposited during both stages of treatment being separated jointly by settling from the refined oils and fats.

WILHELM GENSECKE.
